UNITED STATES PATENT OFFICE.

SAMUEL F. REDHEFFER, OF CHICAGO, ILLINOIS.

DESIGN FOR A GAME-BOARD.

SPECIFICATION forming part of Design No. 21,415, dated March 22, 1892.

Application filed February 23, 1892. Serial No. 422,589. Term of patent 3½ years.

To all whom it may concern:

Be it known that I, SAMUEL F. REDHEFFER, a citizen of the United States, residing at Chicago, in the county of Cook and State of Illinois, have invented a certain new and useful Design for Puzzles; and I do hereby declare the following to be a full, clear, and exact description of the invention, such as will enable others skilled in the art to which it appertains to make and use the same.

The design consists in the novel ornamentation for a game or puzzle board, as herein-after set forth, and shown in the accompanying drawing. Said drawing is a plan view of a game or puzzle board constructed in accordance with my invention. The said drawing shows a game or puzzle board of rectangular shape having its surface divided into spaces by a conventional configuration representing 20 lines running parallel with the several sides of the board. The lines that run parallel with the several sides are of course shorter

as they recede from such side, and the said lines parallel with the several sides of the board meet the parallel lines of the adjacent 25 sides at a right angle. In the center of the board is the representation of a rectangular space, and the surface of the board is further divided into spaces by the arrangement represented, in which some of the lines are discontinued and others intersected by transverse lines. The arrangement is novel and ornamental, and the same is effective, agreeable, and pleasing to the eye.

I claim as my invention—

The design for a game or puzzle board, substantially as shown and described.

In testimony whereof I affix my signature in presence of two witnesses.

SAMUEL F. REDHEFFER.
